UNITED STATES PATENT OFFICE

ROY H. CHARLTON, OF BELMONT, MASSACHUSETTS, ASSIGNOR TO FILING EQUIPMENT BUREAU, INCORPORATED, OF BOSTON, MASSACHUSETTS, A CORPORATION OF MASSACHUSETTS

FILING DEVICE

Application filed August 13, 1927. Serial No. 212,794.

This invention relates to filing devices such as drawers or trays for use in vertical filing systems, and more particularly to means for holding the indexed subject matter in an upright position within a drawer or box and for facilitating the inspection and removal of the same from the drawer.

The drawers herein illustrated as exemplifications of the invention are especially designed as filing drawers for folders or file wrappers adapted to contain papers or other indexed material. This invention is not, however, limited to that particular use, but is applicable to filing cabinets or trays for record sheets, cards, photoplates, X-ray negatives, phonograph records or other filed contents which are intended to be vertically disposed therein.

Difficulty has been experienced heretofore in properly preserving such materials and in conveniently inspecting and removing the same from the filing cabinet, for the reason that, when the drawer or tray is only partially filled, the folders or other indexed material tend to incline from a vertical position and rest obliquely in the tray or flatwise upon its bottom. The folders and their contents are consequently bent out of shape and frequently crushed or broken by the excessive weight of the superposed contents of the drawer or by the handling to which they are subjected in sorting or rearranging. Removal of the drawer contents is also more difficult and the folder can not be opened to inspect its contents without expending the time and effort necessary to remove the desired folder from the drawer. These objections have been overcome to some extent by providing a follower block at the back of each drawer adapted to support the folders and to be moved forwardly and rearwardly of the drawer as the bulk of the filed contents is varied. While this expedient assists in holding the folders upright, an annoying loss of time is required in adjusting its position whenever a few folders are added to or removed from the drawer; the manipulation of the follower is frequently difficult owing to the binding of its frictional attachments; and it occupies considerable of the filing space

in the drawer which should be utilized for the insertion of filing material.

Devices comprising a frame support and a series of flexible pockets carried by transverse bars loosely mounted on the support, have also been provided; but such devices are also objectionable, for the loose mounting of the bars permits the suspended pockets freely to slide longitudinally of the frame, fails adequately to support the filed contents and allows the papers or files within the pockets to tip forwardly or rearwardly, and are not readily adjustable to different numbers of folders or other material to be filed in the pockets.

The principal objects of the present invention are to obviate the difficulties heretofore encountered in the production of an efficient filing device by providing means for dividing a drawer or tray into a plurality of compartments bounded by transverse panels which are flexibly mounted so as to slide a limited distance longitudinally of the drawer under manual pressure but which are ordinarily supported in parallel spaced relation; to provide spring members intermediate the panels to restrain casual movement of the panels and to hold them in said spaced relation; to furnish guides for the panels and means for detachably connecting the panels to the guides, so that the panels may readily be removed without disturbing the guides; and to provide convenient means for attaching the guides to the ordinary filing drawer or tray.

The invention is illustrated in the accompanying drawings which show the embodiment thereof in several optional structural variations of a filing drawer equipped with the aforesaid improvements. In the drawings:

Fig. 1 is a plan view of a filing drawer provided with the recommended form of the improvements;

Fig. 2 is a side elevation of the device shown in Fig. 1;

Fig. 3 is an enlarged transverse section taken on the line 3—3 of Fig. 1;

Fig. 4 shows a detail of the corner construction of Fig. 1 to enlarged scale;

Fig. 5 is an enlarged longitudinal section taken on the line 5—5 of Fig. 1;

Fig. 6 is an enlarged fragmentary view, partly in section showing the manner in which the panel is removably connected to the slideable member illustrated in Fig. 5;

Fig. 7 is a view similar to Fig. 6 illustrating a modification;

Figs. 8 and 9 are perspective views of the slideable member shown in Fig. 7;

Figs. 10 and 11 are views similar to Figs. 1 and 2, illustrating an optional form of guide rail; and

Figs. 12, 13 and 14 are enlarged fragmentary sections taken on lines 12—12, 13—13 and 14—14 respectively of Figs. 10 and 11.

The device comprises in general a drawer or tray of metal, wood or other suitable material, provided with a pair of longitudinal guide rails, preferably disposed above the upper edges of its respective side walls, a plurality of transverse panels, formed of suitable sheet material such as stiff cardboard or fiber board, supports or riders slideable longitudinally of the guide rails, means for detachably connecting each side of the panel to one of said slideable supports, and spring members associated with said guide rails adapted normally to restrain the movement of said supports and thereby flexibly to hold the panels in parallel spaced relation substantially at right angles to the side walls of the drawer, so that the filing folders inserted between the panels are supported in upright position within the drawer.

Referring to Figs. 1 to 6 of the drawings, the filing drawer may be of usual sheet-metal construction having a front 15, side walls 16, and a rear wall 17, the side and rear walls being, as usual, lower than the front wall and the side walls having a wired or doubled upper edge 18. Angle brackets 19 are mounted at each corner of the drawer to support the longitudinal tracks or guide rails 20, and the brackets are preferably attached to the drawer in such a manner that they may readily be affixed to or detached therefrom without employing bolts or rivets passing through the walls of the drawer. A simple and efficient mode of securing the brackets includes the provision of hook bolts 21 which extend through the bracket and engage the wired or folded edge 18 and may be clenched therewith by nuts 22. Other means of attachment may, however, be provided if desired.

The guide rails 20, which extend from end to end of the drawer, above and substantially in the plane of the side walls 16, are preferably provided with inturned longitudinal flanges 23 providing a smooth interior track or channel for slideable supports for the transverse panels 24. The guide rails may be braced at the front and rear of the drawer by transverse tie rods 25 which pass through the respective brackets and through the

guide rails and are locked in position by exterior and interior nuts 26 and 27, respectively, threaded on the rods.

The panels 24 may be formed of metal, wood, cardboard or other thin sheet material of appropriate stiffness and may be rectangular in shape. They are preferably provided with sheet-metal rails 28 which are folded over the upper edge of each panel and suitably secured by rivets 29 or other fastening means and which have sleeve-like ends 30 projecting from each side of the respective panels.

Riders 31 which may consist of a rectangular strip of fiber board, wood or metal, are mounted behind the flanges 23 for sliding movement longitudinally of each of the guides 20, and a hinge member 32 may be secured to the respective riders by rivets 33 as shown in Fig. 5, or by other fastening means. One leaf 34 of each hinge extends inwardly and is received within the respective sleeves 30 of each panel to support the panels transversely of the drawer. The end of each leaf 34 may extend into a recess 35 formed at the upper corner of the panel, to lock the panel in position, but the panels may readily be removed from the supporting leaves by swinging a panel obliquely as indicated by the position 36 of Fig. 1, so that one or both of the leaves are withdrawn from the locking recess to permit the panel to be lifted upwardly.

In order to restrain free movement of the riders 31, compression springs 37 are interposed within the channeled guides between adjacent riders, the ends of the spring members bearing against the ends of the riders. Thus the panels are normally held in spaced parallel relation at right angles to the drawer, but may be moved by hand forwardly, rearwardly or obliquely when desired.

In the modifications shown in Figs. 7 to 9, the riders consist of metal strips 38 having returned side flanges 39. The strips are generally similar in cross-section to the guides 20 and are of such size that they will slide without binding within the guide channels. With this type of rider, the ends of the springs extend within the channeled rider and abut against stops 40 formed by slitting the flanges transversely and bending the resulting tabs inwardly. By such construction the spring members (which may be similar to the springs of Fig. 5) are effective throughout substantially the entire length of the guides and greater freedom of movement of the riders 38 is afforded. The supporting tongue 41, which fits in the sleeve 30 and card recess 35 in the same manner as does the leaf 34 of Fig. 6, may be provided with an eye 42 adapted to be inserted between similar eye members 43 on the rider 38 and to be pivotally connected thereto by a pin 44. The eyes 43 may conveniently be formed by cut-

portion slidably mounted behind the rail flanges and having another portion adapted to project inwardly from the respective rails and to detachably interlock with the panel, whereby the panel is supported transversely of the drawer and may be swung obliquely of the drawer to permit its separation from the hinged member, and spring members disposed within the respective rail flanges and bearing upon the slidable portion of said hinged members to restrain the movement of said members.

8. A filing drawer comprising in combination a drawer, channeled guide rails extending longitudinally of the drawer and having inturned longitudinal flanges, a panel for dividing the drawer space, the panel having a cross bar projecting beyond its lateral edges and the said projecting portions being folded to provide pockets open at the end, hinge members for supporting the panel, one leaf of each member being mounted for longitudinally sliding movement behind the flanges of the respective rails and the other leaf being received within one of said pockets, whereby the panel is suspended transversely of the drawer, and may be swung obliquely of the drawer, each pocket having a portion normally locking the said bar to the respective leaves of the hinge members, so that the panel can not be removed from its supports until it is swung obliquely of the drawer, and spring members disposed within the respective rail flanges adapted to restrain movement of the slidable portion of the hinged member.

9. A filing drawer comprising in combination a drawer, channeled guide rails extending longitudinally of the drawer and having inturned longitudinal flanges, a panel for dividing the drawer space, the panel having a cross bar projecting beyond its lateral edges and the said projecting portions being folded to provide pockets open at the end, hinge members for supporting the panel, one leaf of each member being mounted for longitudinally sliding movement behind the flanges of the respective rails and the other leaf being received within one of said pockets whereby the panel is suspended transversely of the drawer, and may be swung obliquely of the drawer, each pocket having a portion normally locking the said bar to the respective leaves of the hinge members, so that the panel can not be removed from its supports until it is swung obliquely of the drawer.

10. A filing drawer comprising in combination a drawer, channeled guide rails extending longitudinally of the drawer and having inturned flanges, a panel for dividing the drawer space, a hinged member having one portion slidably mounted behind the rail flanges and having another portion adapted to project inwardly from the respective rails and to detachably interlock with the panel, whereby the panel is supported transversely

of the drawer and may be swung obliquely of the drawer to permit its separation from the hinged member.

11. A filing device comprising in combination a drawer, guides associated with the drawer, a panel for dividing the drawer space, said panel being disposed between the guides and having connecting members movable longitudinally of the guides, and spring members carried by the guides, adapted normally to restrain movement of the panel, and means for detachably mounting said guides upon the sides of the drawer.

12. A filing device comprising in combination a drawer having side walls provided with a thickened upper edge, flanged supports arranged at the several corners of the drawer and projecting above the said upper edges, bolts passing through said supports and hooking over said thickened edges for detachably connecting the supports to the drawer, channeled guide rails extending longitudinally of the drawer above said upper edges, and means for fastening the guides to the supports.

13. A filing device comprising in combination a drawer having side walls, longitudinal guide members removably mounted above said walls substantially in the plane of the walls, riders carried by each of said guide members and adapted to slide longitudinally thereof, the riders on one side of the drawer being normally disposed opposite corresponding riders on the other side, individual compression springs carried by the respective guide members between the respective riders, the ends of the springs normally bearing against the riders to restrain sliding movement thereof, and individual panels detachably supported between opposed pairs of riders, the panels being normally held in spaced parallel relation by said spring-positioned riders and being movable longitudinally of the drawer.

Signed by me at Boston, Mass., this 12th day of August, 1927.
